UNITED STATES PATENT OFFICE.

JOSEPH W. BISHOP, OF MUSKEGON, MICHIGAN, ASSIGNOR TO THE BRUNSWICK-BALKE-COLLENDER COMPANY, OF CHICAGO, ILLINOIS, A CORPORATION OF DELAWARE.

MACHINE FOR MAKING BATTERY JARS.

1,407,980.

Specification of Letters Patent. Patented Feb. 28, 1922.

Application filed May 13, 1920. Serial No. 380,982.

To all whom it may concern:

Be it known that I, JOSEPH W. BISHOP, a citizen of the United States, residing at Muskegon, in the county of Muskegon and State of Michigan, have invented certain new and useful Improvements in Machines for Making Battery Jars, of which the following is a specification.

This invention relates to machines of the type disclosed in my co-pending application Serial No. 317702, filed August 15, 1919, for making hard rubber receptacles such as battery jars and the like and more particularly to means for folding and forming the base of such receptacles preliminary to vulcanization.

The primary object of the invention is to provide simple and efficient means for neatly, uniformly and compactly folding the lower edges of the walls of the jar body inwardly and downwardly upon the bottom of the jar and sealing the contacting layers in their folded position ready for vulcanization.

25 A further object of the invention is to provide means for firmly supporting the side walls of the jar during the folding and forming operation so that warping or bulging is eliminated.

30 In the accompanying drawings I have illustrated my invention as now embodied in a working machine, and referring thereto—

Fig. 1 is a top plan view, partly in section, of the device, the parts being in their initial position.

Fig. 2 is a central vertical section, the parts being in the same position as in Fig. 1.

Fig. 3 is a top plan view, partly in section, the parts being in their final position.

Fig. 4 is a side elevation of the device, partly in section, the parts being in the position shown in Fig. 3.

Fig. 5 is an enlarged detailed front elevation of the folding device.

Fig. 6 is an enlarged detailed front elevation of the forming die.

Fig. 7 is a detail perspective view of the folding members.

50 Fig. 8 is an enlarged perspective view of the base portion of a completed jar.

Fig. 9 is a perspective view of the folding head 31 with the folding members 37 removed; and

55 Fig. 10 is a perspective view of the die.

In the drawings like numerals of reference indicate the same parts in the several figures and referring thereto 10 and 11 (Fig. 2) designate portions of the bracket by which the pressure cylinders 12 and 13 are mounted upon the main frame (not shown). A piston 18 is arranged to operate in cylinder 12 and is mounted on a piston rod 17 which is secured to a cross head 16 connected to rods 14. Another piston 19 is carried by the piston rod 20 to operate in cylinder 13 and this piston rod is secured to the forming die 21.

The forming die has oppositely disposed lugs 22 provided with openings 24 to receive and slidably fit about the reduced end portions 26 of the rods 14. This forming die 21 is preferably provided with parallel strips on the operating face 28 thereof, and a plurality of arms or projections 29 extend outwardly from the body portion of the die to engage and operate the folding means.

The folding head 31 is mounted upon the outer extremities of the rods 14 which pass through the lugs 32 on the head and are secured therein by the nuts 33. The body portion of the folding head consists of a hollow frame 34 having a flaring mouth 35. Each of the side and end walls of the frame is formed with an opening 36 therein and a folding member 37 is pivotally mounted in each of said openings. These folding members are preferably constructed with an inwardly projecting flange 37' along the edge opposite to the pivotal connection to provide a substantially rectangular inner operating face 37''. A spring 38 connects each of the folding members with the head and these springs maintain the outer faces of the folding members in contact with the operative inner faces of the corresponding projections 29 on the forming die 21.

In the operation of the machine, the mandrel 39 with the stock 40 wrapped thereon and the bottom piece 41 in place is disposed opposite to the guiding mouth 35 of the folding head in the manner shown in Figs. 1 and 2. Air pressure is now admitted behind the piston 18 through the pipe 42, causing the rods 14 to advance and move the folding head 31 and the forming die 21 toward the mandrel with the parts of the head and die continuing in the same relative position as at the start of the operation. This

forward travel is limited by the adjusting screws 43 on cross rod 16 engaging the cylinder 12. At the completion of the forward movement of the rods, the parts are in the position indicated in dotted lines in Figs. 3 and 4.

Pressure is now admitted through the pipe 30 which still further advances the forming die, the folding head remaining stationary. 10 This relative movement of the forming die and the head causes the inclined face 29' of the projections 29 to coact with the outer faces of the folding members 37 and swing such members inwardly, as shown in Figs. 15 3 and 4. As the folding members thus move, the operating faces 37' disposed at substantially a rectangle to each other thereof cause the free bottom edge of the stock on the mandrel to be folded inwardly and 20 downwardly against the bottom of the jar, and preferably considerable pressure is exerted upon this folded edge in its depressed position to thoroughly seal the layers of rubber together. Simultaneously with the 25 pressing inwardly and downwardly of the free edge, the die face 46 exerts a pressure on the base of the jar and seals the strip 47 thereon. The pressure of the folding members 37 against the sides of the jar during 30 the action of the die face 46 is particularly beneficial as it prevents bulging of these sides which otherwise would be liable to occur.

When the bottom of the jar has been 35 formed in the manner described, the pressure in the pipes 30 and 42 is exhausted and air is admitted in front of the piston 18 through the pressure pipe 48. This causes the rods 14 to move rearwardly, and the 40 springs 28' withdraw the forming die from the folding head so that the parts resume their initial position. The jar is then removed from the machine and placed in the vulcanizer.

45 While the operation of the device has been solely described in connection with the manufacture of battery jars, it will be readily understood that it is adaptable for many other uses and the claims should be so construed.

50 I am aware that changes in the form and proportion and arrangement of parts of my invention may be made without departing from the spirit or sacrificing the advantages 55 thereof and I therefore reserve the right to make all such changes as fairly fall within the scope of the following claims.

I claim:

1. In a machine of the class described, 60 the combination of a mandrel, a folding head, and folding means carried by said head and adapted to fold into co-operative relation to said mandrel.

2. In a machine of the class described, 65 the combination of a mandrel, a folding

head, folding means, hingedly mounted in said head, and means for actuating said folding means.

3. In a machine of the class described, 70 the combination of a mandrel, a folding head, folding members pivotally mounted in said head, and a forming die coacting with said head to actuate said folding members.

4. In a machine of the class described, 75 the combination of a mandrel, a folding head, folding members movably mounted on said head, and a forming die actuating said folding members by relative movement of said head and said die.

5. In a machine of the class described, 80 a mandrel, and a folding head having folding means movable laterally of said head.

6. In a machine of the class described, a 85 mandrel, a folding head, and a plurality of folding members mounted in and movable laterally relative to said head.

7. In a machine of the class described, a 90 mandrel, a folding head, a forming die, and a plurality of folding members pivotally mounted on the head and movable laterally 95 of said head by relative movement of the head and die.

8. In a machine of the class described, a 95 mandrel, a folding head, folding means hingedly mounted on said head, a forming die, and means on said forming die for 100 swinging said folding members inwardly on said head.

9. In a machine of the class described, a 100 folding head, a plurality of folding members hingedly mounted on said head, a forming die, and a plurality of projections on said die coacting with the corresponding folding members on said head to move said members relative to said mandrel. 105

10. In a machine of the class described, a 110 folding head, a plurality of folding members hingedly mounted on said head, a forming die movable relative to said head, a plurality of projections on said die coacting with the corresponding folding members on said head to move said members toward said mandrel during a portion of the travel of said die, and means for returning said members on the completion of the folding operation. 115

11. In a machine of the class described, a 120 folding head, a plurality of folding members hingedly mounted in said head, a reciprocable forming die, means for advancing said folding head into its operative position relative to said mandrel, means for moving said die relative to said head when said head is in said operative position, and means on said die for engaging said members during such relative motion of the die and head to move said folding members toward said mandrel. 125

12. In a machine of the class described, a 130 mandrel, and a folding head comprising a

frame, and a plurality of folding members hingedly mounted in said frame.

13. In a machine of the class described, a mandrel, and a folding head disposed opposite to said mandrel comprising a hollow frame provided with a plurality of openings in the walls thereof, and a folding member hingedly mounted in each of said openings.

14. In a machine of the class described, a mandrel, and a folding head comprising a hollow frame provided with openings in the side walls thereof, and a folding member hingedly mounted in each of said openings and movable laterally of said frame into the interior thereof.

15. In a machine of the class described, a mandrel, and a folding head comprising fixed corner members rigidly connected and folding members pivotally mounted between each adjacent pair of corner members and movable on their pivots toward and from the axis of said head.

16. In a machine of the class described, a mandrel, and a folding head disposed opposite to said mandrel comprising a frame, and folding members hingedly mounted in said frame each having substantially rectangularly disposed operating faces.

17. In a machine of the class described, a mandrel, and a folding head comprising a frame, and a plurality of plates hingedly mounted in said frame substantially on their lower edges, each of said plates having a

flange extending along the upper edge thereof and projecting inwardly therefrom at substantially a right angle to the operating face of the plate.

18. In a machine of the class described, a mandrel, and a folding head disposed opposite thereto comprising a frame, and folding members hingedly mounted in said frame to engage the side walls and the bottom of the jar.

19. In a machine of the class described, a mandrel having a wrapper applied thereto with one edge thereof projecting beyond the end of the mandrel, a folding head disposed opposite to said mandrel, and hingedly mounted folding members each having a laterally projecting flange thereon to engage the projecting edge of the wrapper and press said edge inwardly and downwardly upon the end of the mandrel as said members.

20. In a machine of the class described, a mandrel having a wrapper applied thereto with one edge thereof projecting beyond the end of the mandrel, a folding head disposed opposite to said mandrel, and hingedly mounted folding members movable toward said mandrel to fold said edge inwardly and downwardly upon the end of said mandrel and to press said wrapper against the side walls of said mandrel during such folding operation.

JOSEPH W. BISHOP.
